BOBBIN SUPPORT FOR BATTERY LOOMS

William H. Bahan, Greenville, S. C.

Original application October 13, 1937, Serial No. 168,828. Divided and this application November 15, 1938, Serial No. 240,441

3 Claims. (Cl. 139—249)

This invention relates to a means for holding the lowermost filling carrier or bobbin in a magazine loom so as to prevent its rotation or oscillation prior to being transferred into the shuttle of the loom. More specifically, it relates to a bobbin support which is swingably and oscillatably supported by the transfer arm and which is normally held in supporting position in relation to the lowermost filling carrier in the magazine, said support being oscillatable by cam means on the loom upon the movement of the transfer arm so as to withdraw the bobbin support from the filling carrier.

15 It has been experienced heretofore that vibration in looms causes rotation or oscillation of the lowermost filling carrier, resulting in the end of the thread which extends from the filling carrier becoming broken. When the carrier with a broken or loose end of yarn is finally transferred 20 into the shuttle, the end will not be engaged by the thread gripper. As a result, the filling will not be left in the warp as the shuttle is impelled through the shed and a mispick or thin place in the cloth will appear.

25 It is, therefore, an object of this invention to provide a means for engaging the yarn on the lowermost filling carrier or bobbin in a magazine prior to its transfer into the shuttle of the loom to prevent turning movement thereof, said means comprising a lever pivotally secured on the transfer arm and having its lower end normally contacting the intermediate portions of the yarn on the lowermost filling carrier and means for simultaneously withdrawing the bobbin support from 30 contact with the yarn on the filling carrier upon 35 rotation of the transfer arm.

rotation of the transfer arm.

It is a further object of this invention to provide a bobbin support of the class described which is pivotally and oscillatably mounted near the 40 end of the transfer arm, said support having spring-pressed means for normally holding the lower end thereof in contact with the lowermost bobbin in a magazine of the loom and cam means for rotating said bobbin support away from said lowermost filling carrier upon swinging movement of the transfer arm to transfer said filling carrier into the shuttle.

This is a divisional application of my co-pending patent application, Serial No. 168,828 filed October 13th, 1937.

50 filed October 13th, 1937.
Some of the objects of the invention having
been stated, other objects will appear as the
description proceeds when taken in connection
with the accompanying drawing, in which—
Figure 1 is a transverse sectional view through

the battery and lay of the loom showing the invention applied thereto;

vention applied thereto, Figure 2 is a view similar to Figure 1, but showing the position of the parts during a transfer of the lowermost bobbin in the magazine of the loom to a shuttle; 5

Figure 3 is an isometric view of the invention removed from the loom.

Referring more specifically to the drawing, the numeral 10 denotes a conventional hopper stand 10 for a battery loom which has rotatably mounted therein as at 11 a hopper plate 12, said hopper plate being adapted to cooperate with another hopper plate, not shown, for supporting bobbins of yarn 13. The hopper plate 12 has a toothed gear 14 integral therewith which is adapted to be engaged by advancing ratchet 15, said ratchet being pivotally secured as at 16 to transfer arm 17. The transfer arm is mounted for oscillation around stud shaft 19 and has pivoted to its down-standing leg as at 20 a suitable dog 21. The segment 14 is also engaged by a suitable detent ratchet 25 which is pivoted as at 26 to the hopper stand 10.

When the filling on the bobbin which is in the shuttle 21 becomes exhausted, the dog 21 will be rotated in a counter-clockwise manner by conventional mechanism, not shown, and upon forward oscillation of the lay 28, the bunter 29 which is secured thereto, will contact this dog 30 and rotate the transfer arm 17 to the position shown in Figure 2. The lowermost bobbin 14 will be thereby transferred into the shuttle 27 and upon the restoring of the transfer arm to the normal position as shown in Figure 1 the advancing ratchet 15 will engage the next succeeding tooth in the toothed gear 14 and advance the hopper disk 12 and the next succeeding bobbin to the lowermost position. The structure thus far described is conventional, but is thought necessary to show and describe this much of the old structure in order to more clearly set forth my invention.

In order to normally hold the lowermost bobbin or package of yarn 13 during the operation of 45 the loom and prevent rotation thereof, I have provided a downwardly projecting arm 30 which has a serrated contact portion 31 integral with the lower portion thereof. This portion presses against the yarn on the lowermost package 13, 50 except during the transfer of the bobbin into the shuttle 27.

The arm 30 is adjustably secured to a shaft 40, said shaft likewise being mounted for oscillation in the free end of transfer arm 17 and at such 55

a position that the contact portion 31 will engage the periphery of the lowermost package 13. The other end of the shaft 40 has an arm 40a integral therewith and bent substantially at right angles to the portion 40. When the arm 30 is in a supporting position, the bent portion 40a of shaft 40 is adapted to rest upon a cam portion 25a which is provided on a counter-weight 25b on lower portion of the detent ratchet 25. It will be noted that the lower counterweight portion 25a of the detent ratchet 25 has been built up to such an elevation so that the cam surface 25a will be in the proper elevation for supporting the arm 40a and the bobbin support in the proper position when the bobbin is being contacted. The portion 40a is normally held in contact with the cam surface 25a by means of a suitable torsion spring 41 which is adapted to encircle the intermediate portion of the shaft 40, said spring having one end thereof engaging the downstanding arm 30 and having its other end engaging the top portion of the transfer arm 17.

When a transfer is being made the dog 21 will be thrown to a horizontal position (see Figure 2) at which time the bunter 29 will rotate the transfer arm in a clockwise manner. Then the portion 40a will slide upon the cam surface 25a and cause the shaft 40 and its associated arm 30 to be rotated in a clockwise manner to thereby withdraw the portion 31 from contact with the package of yarn before the transfer arm engages the lowermost bobbin.

In other words, the invention comprises a bobbin support having spring pressed means for normally forcing the bobbin support into contact with the lowermost bobbin and having cam means for withdrawing the support from the bobbin upon the actuation of the transfer arm.

I am aware that bobbin holders have heretofore been provided in which a member is reciprocatably or slidably mounted and engages the filling on the lowermost filling carrier. This structure has the disadvantage of not being drawn directly away from the filling upon a transfer but resulting in a tangential movement with respect to the filling carrier, thus damaging the yarn. By providing a filling carrier holder which is mounted for swinging movement in the arc of a circle, or a true oscillatory movement, the holder is withdrawn from the yarn without chafing the yarn.

In the drawing and specification there has been set forth a preferred embodiment of the invention, and although specific terms are employed, they are used in a generic and descriptive sense only, and not for purposes of limita-

tion, the scope of the invention being set forth in the appended claims.

I claim:

1. In a loom having a lay carrying a shuttle and a rotary hopper for holding a plurality of bobbins, a transfer arm for transferring the lowermost bobbin into the shuttle upon exhaustion or parting of the filling, a finger pivotally mounted on the transfer arm and having its lower end adapted to engage the lowermost bobbin and hold it against turning movement, spring-pressed means for normally holding said finger in engagement with said bobbin, and fixed means engageable by said finger for rotating said finger away from said bobbin upon the movement of said transfer arm to transfer said bobbin into the shuttle.

2. In a battery loom having a hopper and a lay carrying a shuttle, said hopper having means for holding a plurality of bobbins filled with yarn, a pivoted transfer arm for transferring the lowermost bobbin in the hopper into the shuttle upon exhaustion of filling on the bobbin in the shuttle, a finger having its upper end pivotally mounted on the transfer arm and having means on the lower end thereof for engaging the yarn on the lowermost bobbin in the hopper to prevent rotation of said lowermost bobbin, spring means engaging the transfer arm and the finger for holding the lower end of the finger in contact with the yarn on the lowermost bobbin, and means engageable by the upper portion of the finger as the transfer arm is swung downwardly on its pivot to move the lower end of the finger out of contact with the yarn on the lowermost bobbin about to be transferred from the hopper to the shuttle.

3. In a battery loom having a rotary hopper for holding a plurality of bobbins to be transferred into the shuttle in the loom, a transfer arm for engaging the lowermost bobbin in the hopper and transferring it into the shuttle, a finger pivotally mounted at its upper end on the transfer arm and having its lower end normally in engagement with the yarn on the lowermost bobbin, means for normally holding the lower end of said finger in engagement with the yarn on the lowermost bobbin when the transfer arm is in raised position, and other means engageable by the transfer arm upon downward movement of the transfer arm for moving the lower end of the finger from engagement with the yarn on the lowermost bobbin before the transfer arm engages the lowermost bobbin to transfer it into the shuttle.

WILLIAM H. BAHAN.
